COMBINED CARRIER AND RECEIVER FOR A PORTABLE MEDICAL ASPIRATOR

George H. Stoner, Warminster, Pa., assignor to Air-Shields, Inc., Hatboro, Pa., a corporation of Delaware

Filed Nov. 4, 1960, Ser. No. 62,735

Term of patent 14 years

(Cl. D83—1)

Fig. 1.

Fig. 2.

FIGURE 1 is an isometric view of a combined carrier and receiver for a portable medical aspirator embodying my new design; and

The characteristic features of the design reside in the portions shown in full lines.

I claim:

The ornamental design for a combined carrier and receiver for a portable medical aspirator, as shown and described.
